UNITED STATES PATENT OFFICE.

MILTON H. MCKINLEY, OF SEATTLE, WASHINGTON.

CLOTHESLINE.

1,389,681.

Specification of Letters Patent. Patented Sept. 6, 1921.

Application filed February 10, 1920. Serial No. 357,592.

To all whom it may concern:

Be it known that I, MILTON H. MCKINLEY, a citizen of the United States, residing at Seattle, in the county of King and State 5 of Washington, have invented certain new and useful Improvements in Clotheslines, of which the following is a specification.

My invention relates to improvements in clothes lines and the object of my improvement is to provide a clothes line that the 10 clothes may be readily attached to without the use of clothes pins or other fastening means aside from the means embodied in the construction of the line itself.

Another object is to provide a line of this 15 nature that is simple in construction, not expensive to manufacture, and one that will hold the clothes securely when they are fastened therein but which will not damage 20 the clothes and from which the clothes may be readily removed when desired.

A more specific object is to provide a clothes line that is made of a plurality of short sections of wire interlocked with each 25 other and bent in such a manner as to form clothes receiving clips that will not tend to loosen when a hard pull is exerted on the line due to a heavy weight of clothes being sustained thereon.

The invention consists in the novel construction, adaptation and combination of 30 parts of a clothes line as will be more clearly hereinafter described and claimed.

In the accompanying drawings Figure 1 35 is a view in side elevation showing one complete section and two fragmentary sections of a clothes line constructed in accordance with my invention; Fig. 2 is a plan view of the same showing a complete section and a 40 fragmentary section folded side by side. Fig. 3 is a fragmentary view in side elevation showing a slight modification of a part 45 of the device shown in Figs. 1 and 2; Fig. 4 is a fragmentary view in side elevation showing a modification of another part of 50 the device; Fig. 5 is a view partly in section and partly in elevation on broken line 5, 5 of Fig. 4; and Fig. 6 is a view in side elevation showing a modified form of clothes line.

A complete clothes line may be formed 55 of any number of sections according to the length of line desired all of such sections being substantially duplicates so that a description of one section will apply to all.

Referring to the drawings, throughout

which like reference numerals designate like parts, the numeral 7 designates a straight section of wire that is bent at one end to form a loop 8 which is offset to one side of the axis of the straight section as shown in Fig. 2 to facilitate folding the several sections of a line together into a more compact form for handling. The other end of the straight section 7 is bent through substantially one and one-half complete turns to form a circular loop 9, thence projects outwardly from the loop 9 in a short substantially straight section 11. That is substantially parallel with and spaced a distance equal to the diameter of the loop 9 from the straight section 7. At the outer end of the straight short section 11 the wire is bent on an incline as at 12 and is there straightened to form a clothes engaging portion comprising two spaced apart straight sections of wire 13 and 14 arranged to lie on opposite sides of the main wire 7 and connected by a loop or bend 15 that fits over the main wire 7. The section 14 terminates in an inclined end 16 that is substantially parallel with the inclined section 12 and that may, if desired, be doubled on itself as shown at 17 in Fig. 3 to render it less liable to catch and damage the clothes.

The end 16 and the inclined section 12 being on opposite sides of the main wire 7 serve to prevent the clothes engaging clip from being twisted sidewise with respect to the main wire.

The loop or bend 15 that fits over the wire 7 is necessarily bent into a plane at an angle to the plane of the two sections 13 and 14 so that such sections 13 and 14 may lie alongside of or slightly below the wire 7. In Fig. 1 the loop 15 is shown as inclined upwardly from the plane of the sections 13 and 14.

In Figs. 4 and 5 I have shown a form of loop 18 that may be used instead of the loop 15, which loop 18 is formed by doubling the wires closely together for a short distance so that when they rest upon the straight section 7 the end of the loop will project a greater distance outwardly from the wire section 7 than the loop 15 does, thereby making it more easy to insert a piece of clothing thereunder.

In constructing a clothes line a plurality of these sections are secured together by 110 clenching the loops 8 into the loops 9 to form a line of the desired length. If ten-

sion is exerted on the line either by the weight of wet clothes hung thereon or in any other manner such tension will tend to draw the clothes engaging portions 13, 14 and 15 more securely into engagement with the clothes that are held thereby.

The loop 9 acts as a spring and urges the loop 15 toward the wire section 7 at all times but such loop 9 is sufficiently resilient 10 to permit the parts 13, 14 and 15 to be easily raised off of the wire section 7 and folds of clothes to be inserted therebetween.

When the clothes are to be removed from the line a pull from left to right as viewed 15 in Fig. 1, may be exerted on such clothes and they may be readily drawn out of the clip formed by the wire parts 13, 14 and 15 and the straight section 7.

The inclined parts 12 and 16 serve as 20 guides and also serve to prevent the clothes from being drawn back into the loop 9 while the straight section 11 adds to the resiliency afforded by the loop 9.

In Fig. 6 I have shown a clothes line comprising a straight wire section 21 having a closed loop 22 at one end and provided at its other end with a spring loop 23 that merges into a bend 24 that rests against the straight section 21. Continuing from the bend 24 30 the wire bends away from the section 21 in another spring loop 25 and is then straightened into substantially parallel relation to the main section 21 and bent to form a clothes engaging clip comprising two straight portions 26 and 27 that are united 35 by an integral clip 28 that fits over the section 21. The portion 27 terminates in a downturned end 29 that co-operates with one side of the spring loop 25 to prevent the 40 clothes engaging clip from being twisted sidewise from the main wire 21.

In forming a clothes line from the sections shown in Fig. 6 the loops 22 of the several sections are engaged within the loops 23 to 45 form a line of any desired length.

The device shown in Fig. 6 differs from that shown in the preceding figures in the manner of forming the loop and spring at the end where the clothes retaining clip is doubled back on the straight section of wire but is similar to the device shown in Figs. 1 to 5 inclusive in having a clothes engaging portion that fits over and straddles the main wire, that is provided with guiding means 50 to prevent its sidewise displacement from the main wire and that is constructed in such a manner that tension on the line tends to draw the clothes engaging portions more

firmly into engagement with the main portions of the line.

The structure shown in Fig. 6 involves a slightly more simple process in the bending operation necessary to produce the same than does the device shown in Figs. 1 to 5.

In the section shown in Fig 6 the loop 25 65 affords the greater part of the resiliency necessary to permit the clothes engaging portions to be raised out of engagement with the main wire section 21, the bend 24 by its engagement with the main wire 21 serving 70 to prevent the loop 23 from functioning as a spring to any great extent.

My clothes line is strong, simple and not expensive to construct, will hold clothes efficiently without damaging the same, is 75 easy and convenient to manipulate and entirely eliminates the necessity of clothes pins of the various forms now in common use.

From the foregoing description taken in connection with the accompanying drawings 80 the advantages of the construction and of the method of operation of this device will be readily apparent and while I have described the principle of operation of the invention together with the device which I 85 now consider to be the best embodiment thereof, I desire to have it understood that the device shown is merely illustrative and that such changes may be made as are within the scope of the following claim.

What I claim is:

A pinless clothes line formed of connected wire sections, each comprising a straight line section, a loop formed at one end thereof, the other end of the straight line section being bent to form a resilient perpendicularly extending loop, with the end of the wire of the resilient loop extending from the lower side thereof for a short distance parallel to the straight line section and abruptly inclined toward the straight line section to form an abutment, and bent upon itself to provide parallel members spaced slightly below the straight line section and connected by a loop overlying the straight line section, 105 the end of the wire being angularly bent to lie adjacent the abutment section of the relatively short portion extending from the resilient loop to co-operate therewith in limiting movement of clothes mounted on the 110 straight line section toward the resilient loop.

Signed at Seattle, Washington, this 4th day of February, 1920.

MILTON H. McKINLEY.
